UNITED STATES PATENT OFFICE

JAMES HARLEY SKILLIN, OF DALHART, TEXAS

WALL AND PROCESS OF FORMING SAME

Application filed July 5, 1929. Serial No. 376,216.

This invention relates to walls and the process for forming the same, and an object of the invention is to provide for forming a monolithic wall of any desired color which is weather proofed on its exterior surface.

Further objects of the invention are to provide, in a manner as hereinafter set forth, a wall that is strong, compact and durable, thoroughly reliable for its intended purposes, very pleasing in appearance and comparatively inexpensive to manufacture.

With the foregoing and other objects in view, the invention consists in the novel construction, combination, arrangement of parts, and a system for forming the same as will be hereinafter more specifically described and illustrated in the accompanying drawing, wherein is disclosed an embodiment of the invention, but it is to be understood that changes, variations and modifications, may be resorted to, without departing from the spirit of the claims hereunto appended.

In the drawing, wherein like reference characters denote corresponding parts throughout the several views:

Figure 1 is a perspective view, partly in section, of a wall formed in accordance with the present invention.

Figure 2 illustrates one method of forming a wall in accordance with the present invention, and

Figure 3 illustrates a modified method of forming the wall in accordance with the present invention.

In carrying out the invention, the particles of sand, either alone or a mixture with other ingredients, are brought to a state of incipient fusing by an application of heat, which causes a coalescence or an inter-adherence of the sand particles.

It is to be understood that the present invention is adaptable for forming all kinds of walls, such as building walls, grave vaults, building blocks, brick side walks where a weather proof surface is desirable, but the

invention is not necessarily limited thereto, as the invention would be applicable to any of the types heretofore mentioned, whether they would be exposed to the weather or not.

In the description of the invention, the word "sand" is to be understood as those sands found in common sand pits or river deposits in their natural state. It is to be noted that the present invention utilizes no extraneous binding material and the natural sands are utilized without screening, washing or any other treatment.

Referring to the drawing, and particularly to Figures 1 and 2, where the present invention is illustrated in the operation of building of foundation wall, 4 indicates the surface of the ground, in which the foundation wall is being preformed. The ground 4 is formed with a suitable opening 5 of the approximate dimension of the finished wall and supported therein by any extraneous means are a pair of longitudinally extending steel frames 6, 7, of any desired height and thickness. Between the walls of the frames 6, 7, is the form for holding the ingredients of the wall to be presently mentioned.

The interior faces of the plate are preferably formed with layers of heat resisting materials 8, 9, which may be either in the sheet form or may be applied to the same in the form of a wash. Suitable materials for the layers 8, 9, could be asbestos and other fire proof and heat insulating materials. The layers 8, 9, merely protect the forms 6, 7, from excessive heat encountered in the formation of the walls. A suitable shiftable application of heat as indicated generally at 10, is arranged so that it will be movably supported in a suitable manner in proximity to the forms 6, 7. For illustrative purposes in executing the process, the heating means shown is of oxy-acetylene

blow torch 11, but it is within the contemplation of the invention to utilize any practical application of heat, such as electricity, gas, oil burners or the like.

In forming the wall, sand in its natural state from common sand pits in river beds, is deposited in layers of suitable thickness commensurate with the penetrating qualities of the heating means 10, in successive layers. 5 The sand may be mixed with any suitable mineral coloring matter which will give the desirable color under the conditions of heat application used in accordance with the present invention. It is also to be noted that the sand may be used in the wet or dry state. As each layer is deposited, the heating means 10 is applied thereto until the particles of sand reach such temperature as to produce an inter-adherence of the sand particles. 15 This point of temperature should be such that there is only formed a surface co-hesion between the particles as distinct from melting the particles together. The successive layers are deposited with each layer being treated with heat to cause the sand particles of one layer to adhere to the sand particles of the adjacent layer as the wall is built upwardly and the height of the wall is no obstacle to the process, inasmuch as a complete building wall may be formed from foundation to roof from the present process. The wall in the finished state will be one monolithic structure, since each layer has an inter- 20 adherence with the other as the wall is built. 25

When the wall has reached the proportions desired, which for the purpose of illustration is shown in Figure 1 of the drawing, the forms 6, 7, are removed, whereupon the wall is self supporting, by reason of the particles having been incipiently fused together. The finished wall is indicated generally at 12, and after the forms have been removed, either of the faces 13 or the top 14 may be glazed by the blow torch 11, when a temperature is reached 30 which is equivalent to the fusion point or melting point of the sand.

Since the application of heat is local, only the exterior surfaces in direct contact with the flame of the torch will be fused, whereby surface glazing will be applied, that is entirely weather proof and water resisting. 45

While the foregoing description is confined to a building wall of upright character, it is within the contemplation of the invention to apply the forms in horizontal position and build a side walk or other horizontal wall in accordance with the present invention. 50

It is further to be understood that slabs, 55 casing walls, or other types may be made by the present invention.

Referring particularly to Figure 3 of the drawing, wherein a modification of the present invention is shown, block units indicated generally at 15, may be preformed in a factory by filling suitable steel molds with sand of the character hereinbefore referred to and heat is applied to the mold to bring the temperature of the same to the incipiently fusing point hereinbefore referred to. Mineral col-

oring matter may be mixed with the sand, and the sand may be used in either the dry or wet state. When the building blocks 15 have incipiently fused so that they will retain their shape for transportation, they are transported to the location of the building or other wall to be formed and are placed upon each other in courses as will be clearly understood by referring to Figure 3 of the drawing. Between each course of blocks, joints are 70 formed of the same material in the blocks 15, which may be in either the dry or wet state, and the joints are indicated at 16. After a suitable number of courses have been laid, which in Figure 3 is shown as being three in number, the blow torch 17 similar to the torch 11 is brought into proximity to the joint so that the flame thereof will play upon the joint. The flame is maintained upon an area of the joint, until the confusing point thereof is 75 reached, whereby the torch is moved to another area. The confusing of the joints is carried on until the courses form one monolithic structure, whereupon the joints as indicated by dotted lines 17 will be one continuous wall. If it be desired to glaze the exposed weather face of the wall, the operation explained in connection with Figures 1 and 2 of the drawing may be performed. It is within the contemplation of the present invention to allow the walls to be glazed or left in the unfinished or congealed state, either of which will be impervious to normal weather conditions and at the same time will not peel, crack, chip or otherwise deteriorate. 80 85 90

It is thought that by describing in detail herein any particular form structure or arrangement it is not intended to limit the invention beyond the terms of the several claims or the requirements of the prior art. 100

What is claimed is:

1. A process of forming wall structures comprising depositing layers of suitable thickness of sand and producing an incipient fusing of the sand particles by suitable heating means and then fusing the weather surface of the wall by suitable heat to form a glazed weather proof surface. 110

2. A process of forming wall structures comprising depositing a layer of sand in a heat resisting form and producing an incipient fusing of the sand particles by an application of heat, depositing successive layers of sand in the form and causing each successive layer to inter-adhere with the others, 115 by an application of heat and thereafter removing the form and fusing the weather face of the wall by heat to form a glazed weather proof surface on a monolithic wall. 120

3. A process for forming wall structures comprising depositing layers of suitable thickness of sand and mineral coloring matter and producing an incipient fusing of the sand particles by suitable heating means and thereafter fusing the weather surface of the walls 125 130

by suitable heat to form a glazed weather proof surface.

4. A process of forming wall structures comprising depositing layers of suitable thickness of sand and producing an incipient fusing of the sand particles by suitable heating means.

5. A wall structure formed of incipiently fused sand having one face glazed.

10 In testimony whereof I affix my signature.

JAMES HARLEY SKILLIN.
